(57) **CLAIM**

The ornamental design for a cap, as shown and described.

DESCRIPTION

FIG. 1 is a top and front perspective view of a cap, showing
my new design.

FIG. 2 is a top and back perspective view thereof.

FIG. 3 is a bottom and front perspective view thereof.

FIG. 4 is a bottom and back perspective view thereof.

FIG. 5 is a left side view thereof.

FIG. 6 is a top view thereof.

FIG. 7 is a bottom view thereof.

FIG. 8 is a right side view thereof.

FIG. 9 is a front view thereof; and,

FIG. 10 is a back view thereof.

1 Claim, 5 Drawing Sheets
